UNITED STATES PATENT OFFICE.

CHARLES S. LENSTON, OF WORCESTER, MASSACHUSETTS, ASSIGNOR TO HOBBS MANUFACTURING COMPANY, OF WORCESTER, MASSACHUSETTS, A CORPORATION OF MASSACHUSETTS.

FEED-ROLLER SUPPORT.

Application filed June 8, 1927. Serial No. 197,452.

This invention relates to a device for supporting the feed roller, preferably on a double scoring machine, for scoring card-board and similar sheet materials.

5 The principal objects of the invention are to provide means connected with said support by which it will be longitudinally movable and vertically adjustable and capable of regulating the pressure applied to the 10 feed roller; to provide means whereby the adjustment of the pressure on the feed roller can be made permanent for a particular kind or thickness of paper and the 15 adjustment will not be lost or affected by the application of any desired pressure to the roller, and to provide a construction of such a nature that the feed roller will always stop on its descent at a predetermined distance from the feed roll of the machine, and 20 whereby, when a sheet of card-board is introduced, the roller will be capable of rebounding, and also to exert enough friction to prevent the accidental turning of the adjusting screw.

25 Other objects and advantages of the invention will appear hereinafter.

Reference is to be had to the accompanying drawings in which

Fig. 1 is a sectional view of a preferred 30 embodiment of this invention taken transverse to the supporting bar;

Fig. 2 is a horizontal sectional view on the line 2—2 of Fig. 1, showing the feed roller and the supporting bar in plan;

35 Fig. 3 is a vertical sectional view through the center of the bar on the line 3—3 of Fig. 1;

Fig. 4 is a sectional view of the pressure feed roller and its supports on the line 40 4—4 of Fig. 1;

Fig. 5 is a plan of the supporting bar and associated parts;

Fig. 6 is a sectional view on the line 6—6 of Fig. 5; and

45 Fig. 7 is an elevation of one end of the bar with its bearing in section.

It is to be understood that this invention, although capable of other uses, is especially 50 designed for application to a double scoring machine for scoring card-board and other sheet materials. Such a machine is provided with a strong transverse bar 10 ordinarily, and I have shown this bar as having

a slot 11 longitudinally situated and adapted to prevent the turning of the other parts 55 thereon. On this bar is fixed a housing 12 consisting of a single piece of cast iron or other material having opposite machined openings through its sides or flanges 18 adapted to receive the bar 10 and fitting 60 thereon to support the housing. The casting is slit at 13 and a tightening screw 14 is provided having a knob 15 by which it can be turned to tighten the housing on the bar 10. 65

Extending down through the housing at each flange is a screw 16 which holds a key 17 in the slot 11 and, as stated above, holds the housing from turning on the stationary bar 10. Inside the flanges this housing is 70 hollow.

Within the hollow space is a holder 20 which also has a passage therethrough machined and fitting on the bar 10, but this holder is capable of swinging on the bar as 75 at center. I provide means for connecting the holder to the housing and adjusting the holder circumferentially and securing it in adjusted positions. The holder has a passage 21 extending vertically, in the form 80 illustrated, in which is a screw 22 having a head 23 for turning it, and an enlargement 24 at the bottom of a recess in the holder.

On the housing I provide a screw-threaded opening for a screw 25 which has a knob 26 for turning it, in which is a passage which is screw-threaded to receive the threads on the screw 22. Although of course this screw is of smaller diameter than the screw 25, they have the same number of threads per 90 inch, so that any desired pressure can be applied without disturbing the previous adjustment of this screw 22. I provide a set screw or the like 28 for forcing in a soft metal block 29 against the threads of the 95 screw 25. This provides friction so that, when the adjusting screw 22 is turned, the knob 23 will not rotate readily.

Pressure is applied by means of a spring 30 seated in a recess in the bottom of the 100 screw 25 and in an enlarged recess above the passage 21 that has been referred to. The ball 24 at the bottom of the screw rod rests on a seat 31 which is held up by a spring 32, which in turn, rests on an adjusting screw 105 plug 33 in the bottom of the holder. This

screw plug can be turned to adjust the pressure and then secured by a set-screw 34.

The housing is provided with projecting ends 36 which support the shaft 37 of the feed roller 38. This shaft is held in place by being screw-threaded at the end and having a nut 39 screwed on the stud and held by set-screw 40. This nut is located in a recess in the housing projections 36 on both sides.

The roller 38 is provided with roller bearings 42 which have retaining rings 43 at both ends. Each retaining ring has a recess which holds a felt washer 44 for preventing the lubricant from leaking out. The stud 37 is provided with a hole extending centrally from one end and having a passage 45 by which the grease can be forced into the roller bearings. A grease plunger 46 is located in this hole and screwed in to forcibly eject the grease into the roller bearing.

It will be seen that the housing 12 can be moved longitudinally on the bar 10 and clamped to it in any desired location by means of the screw 14. It is prevented from turning on the bar by the keys 17 and their screws 16 which hold them in place.

The housing is not capable of swinging on the bar and is in stationary position after it is set up. The holder 20 swivels on the bar and thus permits the roller 38 to move up and down. Side sway is prevented by the fit of the holder against the inner sides of the housing.

The space between the positively driven feed roll 49 of the machine and the frictionally driven feed roller 38 is adjusted by the screw 22. Thus, after a sheet of cardboard has passed between the two rollers and lifted the roller 38 against the spring pressure, that roller will always stop on its descent at a predetermined distance from the feed roll 49. The spring 32 makes possible the rebound of the roller when a sheet of cardboard is introduced between the rolls 49 and 38. It also causes enough friction to be exerted to prevent the adjusting screw 22 from being turned accidentally by jars and vibrations.

On account of the fact that the two screws 22 and 25 have the same number of threads per inch, any desired pressure can be applied to the roller 38 without changing the adjustment. This screw 25 is held as stated to prevent its turning when the head 22 is turned. Obviously the spring 30 exerts pressure to force the holder down as far as the adjustment of the screw 22 will allow it to go, and yet leave the holder free to swing upwardly if any pressure is applied sufficiently to overcome, in part, the resistance of this spring. The roller bearings of the roller 38 have also been described and also the way of lubricating them.

The bar 10 is supported at its ends in

bearings 50 so as to be capable of being turned slightly to lift all the feed rollers simultaneously and then move them back against the feed roll 49, without losing their individual adjustments. This is done by providing a short rack 51 on the cylindrical surface of the bar and operating it by a worm 52. This worm is located on a shaft 53 and turned by a knob 54. The shaft passes through an adjustable bushing 55 adapted to be set by a set screw 56. After adjustment down into operative position the bar 10 is rendered stationary by the rack and worm construction.

I have not illustrated the machine on which this attachment is mounted, but it will be understood that it comprises the feed roll 49, the stationary bar 10, and scoring devices. This device can be placed on such a machine in place of the ordinary constructions heretofore employed.

Although I have illustrated and described only a single form of the invention I am aware of the fact that changes can be made therein by any person skilled in the art without departing from the scope of the invention as expressed in the claims. Therefore I do not wish to be limited to the exact form shown, but what I do claim is:—

1. In a support for a pressure roller to cooperate with a feed roll to feed sheet material, the combination with a supporting bar and a hollow housing fixed positively to it in stationary position, a holder swiveled on said bar within the housing, means on the holder for supporting a pressure feed roller in a condition free to rotate, and means for adjusting the height of the feed roller and limiting its downward motion toward said feed roll, constituting a stop beyond which the feed roller cannot descend on the rebound downwardly.

2. In a support for a pressure roller to cooperate with a positively driven feed roll to feed sheet material through a machine, the combination with a supporting bar and a hollow housing adjustable along the bar and adapted to be fixed positively to it in stationary position, a holder swiveled on said bar within the housing, means on the holder for supporting a pressure feed roller in a condition free to rotate, means for adjusting the height of the feed roller and limiting its downward motion toward said feed roll, and yielding means for holding the feed roller down under yielding pressure but permitting it to move upwardly under pressure, the adjusting means constituting a stop beyond which the feed roller cannot descend on the rebound downwardly.

3. In a scoring machine, the combination with a driven feed roll and supporting bar, of a housing, means for preventing the housing from turning on the bar, said housing having a space therein surrounding the bar,

a holder located in said space and having means for supporting a feed roller to cooperate with said feed roll of the machine, means for adjusting said holder about the 5 bar, yielding means for resisting its motion, a screw having a knob and mounted in the housing, a screw threaded through the first named screw with threads of the same pitch, and means for holding the outer screw from 10 turning after it is adjusted.

4. In a scoring machine, the combination with a driven feed roll and supporting bar both extending across the machine on parallel axes, of a housing adjustable along said 15 bar, means for fixing the housing to the bar, positive means for preventing the housing from turning on the bar, said housing having a space therein surrounding the bar, a holder located in said space and fitting therein to prevent side-play and having 20 means for supporting a feed roller to cooperate with said feed roll of the machine, means for adjusting said holder about the bar, said means cooperating with the housing and constituting a positive stop against 25 the feed roller moving in one direction, yielding means for resisting its motion in the opposite direction and for restoring it to its extreme position, a screw having a 30 knob adjustable in a circumferential direction with respect to the bar and mounted in the housing, said limiting means comprising a screw threaded through the first named screw with threads of the same pitch, whereby 35 pressure can be applied to the roller without interfering with the adjustment thereof, and means for holding the outer screw from turning after it is adjusted.

5. In a scoring machine, the combination with a feed roll and supporting bar, of a 40 housing, means for fixing the housing to the bar, said housing having a space therein, a holder located in said space, a feed roller supported by the holder to cooperate with 45 said feed roll of the machine in a manner to rotate freely on its own axis, a screw rod connecting the housing and holder having a ball at the lower end fitting in a seat in the holder, a rest engaging the bottom of the 50 ball, and a spring supported by the holder for holding the said rest against the ball.

6. In a scoring machine, the combination with a feed roll and supporting bar both 55 extending across the machine on parallel axes, of a housing adjustable along said bar, means for fixing the housing to the bar, positive means to prevent the housing from turning on the bar, said housing having a space therein, a holder located in said space, 60 a feed roller supported by the holder to cooperate with said feed roll of the machine in a manner to rotate freely on its own axis, means for adjusting the holder about the

bar, said means having a positive stop against the feed roller moving in one direction, means for yieldingly resisting its motion in the opposite direction and for restoring it to its extreme position, and limiting means comprising a screw rod connecting the housing and the holder having a ball at the lower end fitting in a seat in the holder, a rest engaging the bottom of the ball, and a spring supported by the holder for holding the said rest against the ball, the pressure of 65 said spring being adjustable. 70 75

7. In a sheet feeding device, the combination with a supporting bar and a housing fixed to it, of a holder swiveled on said bar, a pressure feed roll supported on said holder in a condition free to rotate, means for adjusting the height of the feed roller and limiting its downward motion, yielding means for holding the feed roller down under pressure but permitting it to move upwardly under pressure, the adjusting means 80 constituting a stop beyond which the feed roller cannot descend on the rebound downwardly, a stud about which said feed roller is rotatable, roller bearings for said stud, and means for applying pressure to force 85 grease into the roller bearing. 90

8. In a sheet feeding device, the combination with a supporting bar, of a holder swiveled on said bar, a pressure feed roll supported on said holder in a condition free 95 to rotate, means for adjusting the height of the feed roller and limiting its downward motion, yielding means for holding the feed roller down under pressure but permitting it to move upwardly under pressure, the adjusting means constituting a stop beyond which the feed roller cannot descend on the rebound downwardly, a stud about which said feed roller is rotatable, and means for connecting the holder with the bar. 100 105

9. In a sheet feeding machine, the combination with a supporting bar mounted to turn in bearings, a series of feed rollers on the bar and means for adjusting the rollers individually, of a rack formed on a circular 110 surface of the bar and a worm meshing with the rack for lifting the feed rollers and moving them back into operative position. 115

10. In a sheet feeding machine, the combination with a supporting bar mounted to turn in bearings, and means for turning it at will and for holding it stationary when adjusted, of a series of feed rollers on the bar and means for adjusting the rollers individually, whereby all of the rollers can be 120 lifted by turning the bar and can be brought down again into operative position without disturbing their adjustments.

In testimony whereof I have hereunto affixed my signature.

CHARLES S. LENSTON.
